UNITED STATES PATENT OFFICE.

JULIAN R. HOLLEY AND EDWARD C. FOWLER, OF BRISTOL, CONNECTICUT, ASSIGNORS TO THE BRISTOL BRASS AND CLOCK COMPANY, OF SAME PLACE.

LAMP-BURNER.

SPECIFICATION forming part of Letters Patent No. 613,276, dated November 1, 1898.

Application filed March 26, 1898. Serial No. 675,350. (No model.)

To all whom it may concern:

Be it known that we, JULIAN R. HOLLEY and EDWARD C. FOWLER, citizens of the United States, residing at Bristol, in the county of 5 Hartford and State of Connecticut, have invented certain new and useful Improvements in Lamp-Burners, of which the following is a specification.

Our invention relates to improvements in 10 lamp-burners; and the object of our improvement is to provide an improved support for the chimney-holding arms.

In the accompanying drawings, Figure 1 is 15 a plan view of our burner, and Fig. 2 is a side elevation of the same.

The burner proper may be of any ordinary construction. The burner-base 3 is provided with upwardly-extended and resilient chimney-holding arms 4, the general form of which 20 is old. Near the middle of the length of these arms they are slit longitudinally and the parts by the side of said slits bent slightly to form eyes 5, as shown. These arms are then tied together by a non-expansile ring 6, which 25 passes through the said eyes 5 of the arms 4. The ring 6 when formed of wire has its ends firmly secured together, so as to make it practically the same as a solid ring. In the drawings we have shown the ends as covered for a 30 short distance by a band 7, which assists in rigidly securing the ends of the wire. The ring although formed of resilient wire is non-expansile because its ends are firmly fastened and the wire will not stretch in an end- 35 wise direction.

We are aware that it is old to make eyes near the upper ends of chimney-holding arms similar to those herein shown and to reinforce said arms by an expansile ring or band, 40 the same in some instances being expansile by means of a loop or other bend in the ring and in some instances by a spiral spring be-

tween the ends of the wire that forms the body of said ring. Our burner differs from the foregoing in two essential particulars— 45 viz., first, we locate the ring below the upper end of the arms and about midway between the base and the extreme upper holding portion at the end of the arms, whereas these prior burners have the ring located at the upper holding end of the arms, and, second, we tie the arms together by a non-expansile band which prevents the arms at the eyes from moving outwardly, while in the prior burners the ring is expansile, so as not to tie the arms 50 together and to permit the arms at the eyes to move outwardly, their own resiliency being reinforced by the resiliency of the expansile ring or band. By our improvement the chimney-arms are or may be of the usual length, 55 so as to reach the proper distance above the bottom of the chimney, while the non-expansile ring serves to tie the arms together and give them the rigidity of shorter arms, practically the same as if the length of the arms 60 was only the portion which is above the ring. At the same time all of the arms may move bodily together slightly in a lateral direction when tied together by the ring to a greater extent than if the arms extended from a rigid 65 base located where the ring is placed.

We claim as our invention—

A lamp-burner having the resilient chimney-holding arms 4 extending upwardly from its base, and a non-expansile ring secured on 75 said arms at a point about midway between their upper bearing ends and the said base, substantially as described.
